UNITED STATES PATENT OFFICE.

EARL L. URBAN, OF CLEVELAND, OHIO, ASSIGNOR TO MAZZOLINI ART CRAFT COMPANY, A PARTNERSHIP COMPOSED OF PRIMO MAZZOLINI, JOSEPH C. MAZZOLINI, AND ALFONSO MAZZOLINI, OF CLEVELAND, OHIO.

DESIGN FOR A LIGHTING FIXTURE.

Application filed May 15, 1925. Serial No. 13,445. Term of patent 7 years.

To all whom it may concern:

Be it known that I, EARL L. URBAN, a citizen of the United States, residing at No. 1256 East 123rd St., Cleveland, in the county of Cuyahoga and State of Ohio, have invented a new, original, and ornamental Design for Lighting Fixtures, of which the following is a specification, reference being had to the accompanying drawing, forming part thereof.

The figure represents a front elevation of a lighting fixture, showing my new design.

I claim:

The ornamental design for a lighting fixture, as shown.

EARL L. URBAN.
